UNITED STATES PATENT OFFICE.

EDWARD J. COOK, OF ROCHESTER, NEW YORK, ASSIGNOR OF ONE-HALF TO DONALD P. FALCONER, OF ROCHESTER, NEW YORK.

METHOD OF SPLICING RAILS.

1,193,238.

Specification of Letters Patent.

Patented Aug. 1, 1916.

Application filed April 16, 1915. Serial No. 21,730.

To all whom it may concern:

Be it known that I, EDWARD J. COOK, a citizen of the United States, residing at Rochester, in the county of Monroe and State of New York, have invented certain new and useful Improvements in Methods of Splicing Rails, of which the following is a specification.

My invention relates to a method of joining track rails, particularly the rails of street railways.

Difficulty has been encountered in street railway work in so connecting the rails as to avoid what is known as "cupped-joints". These cupped joints are usually caused by the action of the wheels on the head of the rail which tends to cold roll the same, throwing a wave of metal ahead of the wheel, so that this wave of metal will broom off the running-off rail, resulting in a short period of time in a cup on the receiving rail. When the track is constructed in a paved street, it is impossible to do any work of maintenance on the joints during the life of the rails without the removal of the pavement at considerable expense.

It is the object of my invention to provide a method of connecting the rails whereby the ends of adjacent rails are not only drawn close together and firmly held in that position, but to also more particularly provide for placing an initial longitudinal compression in the ends of the rails which will obviate the difficulty mentioned due to the action of the wheels upon the rails.

In the accompanying drawings:—Figure 1 is a side elevation of portions of two rails before they have been joined together. Fig. 2 is a section on the line 2—2 of Fig. 1. Fig. 3 is a side elevation of the same rails showing an undrilled bar applied thereto in heated condition for the purpose of indicating thereon the proper position for the holes in carrying out one step of my method.

Fig. 4 is a section on the line 4—4 of Fig. 3. Fig. 5 is a side elevation of the rails showing a drilled splice bar applied thereto, this view being somewhat diagrammatic in character to better explain the method which I employ. Fig. 6 is a side elevation of the rails showing a splice bar applied thereto in connected form.

Like parts are represented by similar characters of reference in the several views.

55 In carrying out my method in its broad-

est aspect various means may be employed to obtain the result sought, *i. e.*, that of placing an initial compression in the ends of the rails. The most simple and practical way now known to me, however, has been shown in the drawings and will now be explained, this means consisting in the employment of splice bars applied in the following manner:

Referring to the drawings, 1 and 2 represent portions of adjacent rails shown provided with the usual openings, 3 and 4 respectively, for the reception of the bolts or rivets which connect the bars thereto. In the usual way of connecting these bars, the bars are also initially provided with rivet or bolt holes which register with the holes in the rails. In my improved method, the splice bars will be initially provided with holes which will be out of registry with the rail openings, it being necessary, in order to apply the bars to the rails, to first heat and expand the bars for the purpose of bringing the openings therein in registry with the rail openings. The bars are then riveted or bolted to the rails in this heated state, the contraction of the bars in cooling causing the ends of the rails to be drawn tightly together and an initial compression placed therein.

For the purpose of drilling the openings at the proper places in the bars, a jig may be made by placing two rails together as closely as they may be laid, such as shown in Fig. 1, applying thereto an undrilled bar, represented by 5, the metal of which has been expanded by heating to a low red. Marks are then placed on this bar, for instance at the intersection of the lines *a* and *b*, to register with the openings 3 and 4 in the rails. After the bar thus marked has cooled, openings are drilled in the same in accordance with the marks and the bar thus drilled may be used as a jig for the purpose of drilling the holes in the other splice bars.

In Fig. 5 I have shown an unheated splice bar, thus drilled, laid against the rails to illustrate the relative position of the openings of the bar and rails before the bar has been heated, which shows that the openings in the bar are out of registry with those in the rails; the openings in the bar being shown in full lines and those in the rail by dotted lines, the position of the open-

ings relatively to each other, however, being exaggerated somewhat.

It will be understood from this that after having once made a proper jig, commercial splice bars properly drilled may be delivered at the point of installation ready for heating and application. In applying the bars, as before stated they will be heated to the proper temperature to bring their 10 openings in registry with the rail openings, which heating will expand the metal of the bars. The bars are then connected with the rails either by hot riveting or bolting as may be desired, and the bars left 15 to cool, whereupon the contraction of the bar in cooling will pull the ends of the rails tightly together, as shown in Fig. 6, causing a compression of the ends of the rails, the amount of this compression of course 20 varying according to the drilling of the splice bars in relation to the drilling of the webs of the rails, but placing an initial compression strain upon the cross section of the rail within the limits of the splice bar 25 length.

I have demonstrated in a practical way that this method of joining the rails and placing a compression therein will obviate the difficulty mentioned, as the wave action 30 caused by the wheels will be transmitted from one rail to another without theoretical change in the elevation of the wheel in passing over the joint, so that there will be no opportunity for the running-off rail to become 35 broom and the receiving rail to become cupped.

Having thus described my invention I claim:-

1. The method of joining metal track 40 rails, consisting in placing the ends of the rails together and securely fastening the

same and placing an initial longitudinal compression in the ends of said rails.

2. The method of joining rails consisting in applying to the rails a connecting element expanded beyond its normal condition and applying fastening means while said connecting element is in its expanded condition and then permitting said connecting element to contract for the purpose specified. 45

3. The method of joining rails consisting in placing an initial longitudinal compression in the ends of the rails by applying thereto a connecting element fastened to 50 said rails while said element is in an expanded condition and then permitting said connecting element to contract. 55

4. The method of connecting rails consisting in the placing of an initial longitudinal compression in the rail ends by fastening to same an expanded connecting element, and allowing same thereafter to assume its normal condition, substantially as 60 specified. 65

5. The method of connecting rails consisting in providing the ends of the rails with openings, applying to the ends of adjacent rails a bar also formed with openings such that when the bar is in a heated state 70 the openings therein will register with the openings in the rails, inserting fastening means through the openings in the bar and rail ends while the bar is in its heated state, and then permitting said bar to cool and contract. 75

In testimony whereof, I have hereunto set my hand this 10th day of April, 1915.

EDWARD J. COOK.
